CLAIM

The ornamental design for an angled mounting bracket for an electronic device, as shown and described.

DESCRIPTION

FIG. 1 is a front, top, right side perspective view of an angled mounting bracket for an electronic device showing our new design in an environment of use;

FIG. 2 is a front, top, right side perspective view of the angled mounting bracket for an electronic device of FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is top plan view thereof; and,

FIG. 8 is a bottom plan view thereof.

Broken lines in FIG. 1 illustrate environmental subject matter and form no part of the claimed design. Broken lines in FIGS. 2-5 illustrate portions of the angled mounting bracket for an electronic device that form no part of the claimed design.

1 Claim, 7 Drawing Sheets
